UNITED STATES PATENT OFFICE

STANLEIGH MEGARGEE, OF NEW YORK, N. Y.

BIT

Application filed August 10, 1931. Serial No. 556,244.

This invention relates to bits for horses, and is designed particularly for riding.

In the biting and handling of riding horses, it is desirable, and, in fact, necessary, particularly with show horses being maneuvered in the ring, and polo ponies, which are handled at high speed on the field, that a bit be provided which will give proper and sure control of the horse at all times; to the action of which he will quickly respond, and yet the bit must be of such construction as to not injure the mouth even when applied or manipulated with a good deal of force.

As here shown, my invention is disclosed in connection with a combined curb and snaffle bit, which is the type ordinarily used for riding.

In order that the invention may be clear to those skilled in the art, I have illustrated in the accompanying drawing one physical embodiment of my invention and that the best now known to me.

In the drawing:—

Figure 1 is a side view of the bit of my invention, so much of the bridle parts as is necessary being disclosed, and the outline of the lower or jaw portion of a horse's head is conventionally shown.

Figure 2 is a view in perspective of the bit. Figure 3 is a sectional view substantially on a line passing through pins 13 and 24.

Referring to the drawing by numbers, like numbers indicating like parts in the several views, 10 indicates the bit-bar, which, as shown, is a strip of metal of proper thickness and of very considerable width, so that, as shown in Figure 1, it takes a wide bearing on the gums of the lower jaw; its action on the jaw is distributed over a wide area, and, by reason of this width, punishing or injurious pressure against the gums and the jaw bone is avoided. The said bit-bar 10 is provided centrally with a port or curved portion which spans and arches over the tongue of the horse.

The bit 10 is pivotally mounted in the cheek-bars 12, as best shown in Figure 3 by means of a pivot pin 13, preferably in the longitudinal axis of the bit-bar 10 and of any suitable formation, so as to connect the cheek-bars 12

and the bit in pivotal relation. With this construction, it will be seen that since the cheek-bars are rotatable relative to the bit-bar, pull upon the cheek-bars 12 will not rotate or displace the bit-bar 10, but it will remain always in the position shown, namely, flat against the gums of the lower jaw of the animal, the movements of the cheek-bars 12 about the pivot 13 of the bit-bar 10 having no turning effect on the bit-bar 10.

The cheek-bars will be provided with the snaffle loops 14 to which the snaffle reins 15 will be attached and function in the usual manner. At their upper ends, the cheek-bars 12 will be provided with the loops or rings 16 for the cheek-straps 17 of the head-stall, and to the rings 16 will be attached, in the usual manner, the curb-strap or chain 18 which passes under the lower jaw of the animal from one side to the other.

The lower limbs of the cheek-bars 12 will be provided with the loops 19 for the lip-strap 20, which is engaged with the curb chain, as shown, to maintain the parts in the same relative position, and at their extreme lower ends the cheek-bars 12 have the ring-receiving eyes 21, in which are mounted the rings 22, to which the curb-reins 23 are attached.

The bit-bar 10 is provided at each end with a pin 24, off-set from the pivot-pin or swivel 13 and engaging an arcuate slot 25 formed in the cheek-bars, which pin 24 permits movement of the cheek-bars 12 without affecting the bit-bar 10. This construction provides a novel compact arrangement in which each snaffle loop 14 is positioned rearwardly of the pivot point 13 and each slot 25 is disposed opposite to the snaffle loop and forwardly of the pivot point. In full lines in Figure 1 the cheek-bars are shown in an intermediate position, and in dotted lines is shown in their two extreme positions.

With the construction shown and described, it will be seen that in the position of the bit shown in full lines in Figure 1, with the curb-reins relaxed, there will be no pressure exerted by the curb-chain or strap, and the animal will be handled in the usual way by the snaffle reins, without exerting any control by the curb. In all positions of the bit,

the bit-bar 10 will lie, as shown, flat upon the gums of the lower jaw. When pressure is exerted on the curb-reins 23, the cheek-bars 12 will be rotated about the pivot or swivel 13, and as the curb-chain loops 16 are correspondingly moved, pressure of the curb will be exerted on the underside of the lower jaw, the pins 24 riding in the slots 25. Even when the pressure is exerted to a maximum, it will be seen that the bit-bar 10, with its wide contacting surface, by reason of the play between the cheek-bars 12 and the bit-bar 10 provided for by the pins (24) and slot (25) connections, will remain always in the normal position shown, there being no action tending to rock or tilt the bit-bar 10. The curb-chain 18, however, will be exerting its action on the underside of the lower jaw to give the proper control of the animal; such curb-chain limiting pin and slot movement in one direction, and the lip-strap 20 limiting movement in the other direction.

With this construction, the parts being properly adjusted, there is no chance of turning the bit-bar in the mouth, to cause objectionable lacerations, or, as sometimes happens with the ordinary curb, fracture of the jaw bone, the restraining effect of the curb being effected on the underside of the jaw, instead of by means of the bit-bar in the mouth against the gums and the inside of the lower jaw. This is a decided advantage and provides a bit which, while effective in controlling the animal, is humane in its action and does away with injuries which not infrequently occur when maneuvering a horse at high speed. In effect, the bit-bar simply forms a fulcrum for the cheek-bars, which, with lever action, draws the curb against the underside of the lower jaw, and the width of the bit-bar so distributes pressure, its position remaining unchanged, that danger of injury to the inside of the jaw is eliminated.

The pins 24 and the arcuate slots 25, which slots are preferably, and as here shown, struck from the center of the pivot-pin or swivel 13, are provided in order that the bit-bar may be maintained always in its flat position on the lower jaw and not be tilted in a perpendicular position. The slots 25 are so placed that the cheek-bars 12, swivelling on the pivot pins 13, cannot be thrown or moved to abnormal positions in either direction and insures such relation of the parts as to keep the bit always in position for proper control of the animal. In other words, the mouth position of the bit-bar 10 is not changed in the ordinary and usual manipulations of the bit.

From the foregoing it will be seen that a very effective and, at the same time, humane bit is provided, and one which eliminates many of the injuries inflicted by bits now on the market when used in hard riding in the show ring or in the polo or hunting fields.

It will be understood that such changes in construction from that shown and described as are within the skill of a mechanic may be made without departing from the range of my invention.

I claim:—

1. In a bit of the class described, the combination of a bit-bar having a relatively wide substantially flat jaw-engaging undersurface, a pivot-pin at each end of said bit-bar, slotted cheek-bars mounted on said pivot-pins for pivotal movement and provided at their upper ends with cheek-strap connections and at their lower ends with curb-rein connections, and a pin at each end of said bit-bar offset from said pivot-pins to engage the slots in said cheek-bars and permit only limited relative pivotal movements of said bit-bar and cheek-bar without shifting the mouth position of said bit-bar.

2. In a bit of the class described, the combination of a bit-bar having a relatively wide substantially flat jaw-engaging undersurface, a pivot-pin at each end of said bit-bar, cheek-bars mounted on said pivot-pins for pivotal movement and provided at their upper ends with cheek strap connections and at their lower ends with curb-rein connections, said cheek-bars being provided with snaffle loops positioned rearwardly of the pivot point and having slots disposed opposite to said snaffle loops and forwardly of said pivot point, and a pin at each end of said bit-bar located adjacent the forward edge of the same to engage the slots in said cheek-bar and permit only limited relative pivotal movements of said bit-bar and cheek-bar without shifting the mouth position of said bit-bar.

In testimony whereof I affix my signature.

STANLEIGH MEGARTEE.
